UNITED STATES PATENT OFFICE.

JACOB SALATHE AND JOHN TAMBERLIN, OF PHOENIXVILLE, PENNSYLVANIA.

WINDING-SPOOL SPINDLE AND BEARING THEREFOR.

SPECIFICATION forming part of Letters Patent No. 790,526, dated May 23, 1905.

Original application filed April 29, 1904, Serial No. 205,527. Divided and this application filed August 16, 1904. Serial No. 220,891.

To all whom it may concern:

Be it known that we, JACOB SALATHE and JOHN TAMBERLIN, citizens of the United States, residing in Phoenixville, county of Chester, 5 State of Pennsylvania, have invented certain new and useful Improvements in Winding-Spool Spindles and Bearings Therefor, of which the following is a specification.

Our invention relates to spinning-machines, 10 and particularly to the improved construction of spool-spindle and bearing therefor herein-after fully described in connection with the accompanying drawing, and the novel features of which are specifically pointed out in the 15 claim.

The drawing is a vertical section of our improved winding-spool spindle and bearing, showing the same mounted upon the usual spindle-rail and in connection with the radius- 20 arms which carry the single-thread spools as described in our pending application, Serial No. 205,527, filed April 29, 1904, of which the present application is a division.

The winding-spool 5, upon which the twist- 25 ed-together threads from the usual separately-mounted spools are wound, is carried upon the pulley-sleeve 6, which, as shown, is adapted to engage the pulley-sleeves of said separate spools, (not shown,) so as to be rotated 30 in a reverse direction, as is well known and more fully described in our pending application referred to. This pulley-sleeve 6 loosely incloses the bolster-case 10 and is carried upon the step-bearing 11 within the latter by 35 means of the concentric tubular spindle 12, forming part thereof and extending into the bore of the bolster-case, in which it is centered by a bottom collar 13, bearing upon a suitable step-bearing washer or seat 14 and 40 by an upper collar 15. A central tubular bolster 16 within the bolster-case 10 rises loosely

through the spindle 12 with its pulley-sleeve 6 and provides a passage-way for the central carrier-rod 17, upon which is carried the guide-ring to which the required up-and-down movement is transmitted by means of a cam or other suitable means. The bolster-case 10 is firmly secured to the spindle-rail 20 of the machine by means of a nut 21 upon its lower end, with a distance sleeve and washer 23 strung thereupon between said nut and the bottom of the spindle-rail to provide for carrying the delivery-spools upon radius-arms 24, pivoted upon said distance-sleeve, as described in said pending application. The 55 bolster-case 10 thus forms an annular oil-receptacle, in which the tubular spindle 12, with its collars 13 and 15, is retained in vertical position while being rotated upon the step-bearing washer 14, with an annular wall of 60 oil both inside and outside of said tubular spindle, thus providing a very satisfactorily-supported and thoroughly-lubricated spindle-mounting.

What we claim is—

A spindle mechanism comprising a tubular bolster-case 10 having a central bolster 16 therein, a tubular spindle 12 inclosing said bolster without contacting therewith, and having top and bottom collars centering the 70 same in said bolster-case and an annular seat in the latter, and a concentric pulley-sleeve forming a rigid portion of said tubular spindle substantially as set forth.

In testimony whereof we affix our signatures 75 in the presence of two witnesses.

JACOB SALATHE.
JOHN TAMBERLIN.

Witnesses:

H. C. GILLINGHAM,
JOHN J. CARTER.
